(57) **CLAIM**

The ornamental design for a low power module for controller of transport climate control system, as shown and described.

DESCRIPTION

FIG. 1 is a top perspective view of a low power module for a controller of a transport climate control system showing our new design;

FIG. 2 is a bottom perspective view thereof;

FIG. 3 is a front elevation view thereof;

FIG. 4 is a left side elevation view, the right side being a mirror image thereof;

FIG. 5 is a top plan view thereof; and,

FIG. 6 is a bottom plan view thereof.

We note that the low power module for a controller of a transport climate control system shown in FIGS. 1-6 can be used, for example, in transport climate control applications. The controller can be used to control environmental condition(s) (e.g., temperature, humidity, air quality, and the like) within a climate controlled space of a transport unit (e.g., a truck, a container (such as a container on a flat car, an intermodal container, a marine container, a rail container, etc.), a box car, a semi-tractor, a bus, or other similar transport unit).

The broken lines in the drawings depict portions of the module that form no part of the claimed design. The dash-dot-dash broken lines define the bounds of the claimed design and form no part thereof.

1 Claim, 5 Drawing Sheets
